(57) **CLAIM**

The ornamental design for the scaffold anchor, as shown and described.

DESCRIPTION

FIG. 1 is a front right perspective view of a scaffold anchor showing my new design.

FIG. 2 is a rear perspective view of the scaffold anchor of FIG. 1.

FIG. 3 is a front side view of the scaffold anchor of FIG. 1.

FIG. 4 is a rear side view of the scaffold anchor of FIG. 1.

FIG. 5 is a left side of the scaffold anchor of FIG. 1.

FIG. 6 is a right side view of the scaffold anchor of FIG. 1.

FIG. 7 is a top view of the scaffold anchor of FIG. 1; and,

FIG. 8 is a bottom view of the scaffold anchor of FIG. 1.

The dashed lines in the figures are for the purpose of illustrating portions of the scaffold anchor and form no a part of the claimed design.

1 Claim, 8 Drawing Sheets
